Primary Examiner—Prabhakar Deshmukh(74) *Attorney, Agent, or Firm*—McDermott, Will & Emery(57) **CLAIM**

The ornamental design for a razor cartridge package, as shown and described.

DESCRIPTION

FIG. 1 is a front perspective view of a razor cartridge package showing my new design;

FIG. 2 is a front elevational view thereof;

FIG. 3 is a rear elevational view thereof;

FIG. 4 is a side elevational view thereof;

FIG. 5 is a top plan view thereof;

FIG. 6 is a bottom plan view thereof;

FIG. 7 is a plan view thereof; shown in an unfolded condition;

FIG. 8 is a perspective view of second embodiment of a razor cartridge package;

FIG. 9 is a front elevational view of FIG. 8;

FIG. 10 is a rear elevational view of FIG. 8;

FIG. 11 is aside elevational view of FIG. 8;

FIG. 12 is a top plan view of FIG. 8;

FIG. 13 is a bottom plan view of FIG. 8; and,

FIG. 14 is a plan view of FIG. 8; shown in an unfolded condition.

The broken lines are for illustrated purpose only and forms no part of the claimed design.
